UNITED STATES PATENT OFFICE

FRANK A. DONALDSON, OF ST. PAUL, MINNESOTA

SPARK ARRESTER FOR INTERNAL COMBUSTION ENGINES

Application filed February 21, 1929. Serial No. 341,675.

This invention relates to spark arresters for internal combustion engines and is in the nature of a modification of the spark arrester disclosed and claimed in my United States application, executed of even date herewith entitled "Spark arrester for internal combustion engines," Serial Number 341,674, filed February 21, 1929.

In the accompanying drawings, like characters indicate like parts throughout the several views.

Referring to the drawings:

Fig. 1 is an axial sectional view of the arrester; and

Fig. 2 is a section taken on the line 2—2 of Fig. 1.

The numeral 3 indicates a tubular sheet metal casing, which casing comprises the main body of the arrester and which is provided at its intake end with a head 4 and at its outlet end with a head 5. These heads 4 and 5 are illustrated as being secured to their respective ends of the casing by means of flange and rolled-edge connections 6.

The head 4 at the intake end of the arrester is provided with an axial internally threaded sleeve 7 that is illustrated as having screw threaded engagement with an exhaust pipe 8, which pipe may be assumed to lead to the exhaust manifold of an internal combustion engine not shown. The head 5 at the outlet end of the arrester is punched out at its center to form an axial outlet opening 9 projecting outward from the edge of which is an annular collar 10. Extending inward from the outlet opening 9 to the interior casing is an outlet tube 11, the outer edge portion of which fits within the annular collar 10 and is suitably secured thereto by welding or the like at 12.

Within the tubular casing 3 is a series of axially spaced baffle partitions. The baffle partitions near the intake end of the casing is indicated by the numeral 12a, the intermediate partition by the numeral 13, and the partition near the outlet end of the arrester by the numeral 14. These baffle partitions 12a, 13, and 14 divide the interior of the casing into several compartments, to wit: a compartment 16 at the intake end of the cas-

ing, a compartment 17 at the outlet end of the casing and intermediate compartments 18. In the baffle partitions 12a, 13 and 14 near the outer edge portions of each thereof is formed an annular series of circumferentially spaced deflecting blades or veins 15 for successively imparting a whirling motion to spark laden gases passed through the interior of the casing.

It should now be noted that the baffle partition 12a near the intake end of the arrester is closed at its central portion inside of the annular series of deflecting blades formed near the outer portion thereof, and that the intermediate baffle partition 13 and the baffle partition 14 near the outlet end of the arrester are provided with axial outlet openings 14a. It will further be noted that the outlet tube 11 extends close to the baffle blades in the last partition near the outlet end of the arrester and that the diameter of the outlet tube 11 is preferably not greater than the distance between the inside portions of circumferentially spaced blades 15 in the partition 14.

All of the spark laden gases delivered into the compartment 16 at the intake end of the casing from the exhaust pipe 8 will, of course, be caused to pass through the oblique deflecting blades in the baffle partition 12a, and will be caused to whirl at relatively high velocity upon entering the first intermediate compartment 18. The sparks thus being whirled at high velocity will be thrown outward by centrifugal force, and will travel close to the sides of the casing.

By throwing the heavier than air particles, such as hot sparks of carbon, toward the side of the casing in the intermediate compartment, it will be apparent that the gases near the axis of the casing will be clean and free from sparks or the like. These clean gases, near the axis of the casing in the first intermediate compartment 18 will be passed uninterruptedly into the second compartment through the axial opening 14a, in the intermediate baffling partition 13, and the spark laden gases near the sides of the casing will pass into the second inter-

mediate compartment through the deflecting blades 18, in said baffle partitions 13. The spark laden gases thus passed through the second intermediate compartment will by the 5 action of the last noted deflecting blades be stepped up in their whirling motion thus keeping all the sparks close to the side of the casing.

10 The clean gases near the axis of the second intermediate compartment will pass directly through the axial opening 14a in the deflecting partition 14 near the outlet end of the arrester to the aligned outlet tube 11 and therethrough to the open atmosphere, and 15 spark laden gases near the side of the casing will pass through the deflecting blades in the baffle partition 14 to the compartment 17 at the outlet end of the arrester and will again be stepped up in their whirling motion. 20 The sparks thus passed into the compartment 17 will be thrown outward and toward the outlet end of the casing and will whirl around in the space between the outlet tube 11, and the sides of the casing until 25 they become spent, and the gases passed into the outside portion of the compartment 17 will reverse their course of travel and pass through the open inner end of said outlet tube 11 to the atmosphere with the other 30 cleaned gases.

It should however be understood that a large percentage of the sparks entering the inlet end of the arrester will, due to their long course of travel caused by the whirling motion imparted thereto by the several series of deflecting blades, become entirely spent in the compartments preceding the compartment 17 at the outlet end of the arrester and therefore those sparks entering 35 said compartment 17 will in most cases have become so reduced in size that they will quite readily become entirely spent. The compartment 17 having the outlet tube extended therein as illustrated may be considered 40 a spark trap.

The arrester is illustrated as being employed in a vertical position but may be employed efficiently in a horizontal position.

When a device is used in a vertical position, however, rain water may come through 50 the outlet tube 11 when the arrester is inoperative. This water will drop through the several baffle partitions and on to the head at the intake end of the arrester, and 55 through small drain holes 19 therein. The water will not be allowed to drop into the exhaust pipe 8 for the reasons that the central portion of the partition 12a directly above the open end of the exhaust pipe is 60 closed so that the water will be caused to drop through the blades 15 in the partition 12a and on to the head 4 outside of the open end of the exhaust pipe where it will be retained by the inwardly projecting sleeve 7 65 until it has drained out through the holes 19.

What I claim is:

1. A spark arrester comprising a tubular casing having a head at each end thereof, an intake passage near one end of the casing and an axial other passage in the head at the outlet end of the arrester, axially spaced partitions in said casing, an annular series of circumferentially spaced deflecting blades or veins formed near the outer edge of each of said partitions close to the side of the casing, the baffle partition near the intake end of the arrester having a closed central portion and the partition near the outlet end of the arrester having an axial opening, and an outlet tube extending inward from the axial outlet passage in the head at the outlet end of the arrester and terminating short of the partition at the outlet end of the arrester. 70

75 2. A structure defined in claim 1 in which the open inner end of the outlet tube is of greater diameter than the axial opening in the baffle partition at that end of the arrester, but of less diameter than the distance between the inner edge portions of diametrically opposed blades in said partition. 80

85 3. A spark arrester comprising a tubular casing having a head at each end thereof, an axial inlet in the head at one end of the arrester and an axial outlet in the head at the other end of the arrester, a series of baffle 90 partitions in the casing that are spaced axially from one another and from said casing heads to form end compartments and intermediate compartments, an annular series of circumferentially spaced deflectors near the 100 outer portion of each of said baffle partitions, the partition near the intake end of the arrester being closed at its central portion and the intermediate partition and the partition at the outlet end of the arrester having an 105 axial opening and an outlet tube extending inwardly from the axial outlet into the compartment at the outlet end of the arrester and terminating short of the partition at the outlet end of the arrester and 110 spaced from the sides of the casing slightly more than the distance between the casing and the inside of the deflectors.

115 4. A spark arrester comprising a tubular casing having an inlet in one end thereof and an axial outlet near the other end thereof, an axially spaced series of baffle partitions in said casing and an annular circumferentially spaced series of deflecting blades or veins in each of said baffle partitions near the outer edge portions thereof, the first baffle partition at the intake end of the arrester being closed to incoming gases at its central portion so that all of the incoming 120 spark-laden gases will be passed through the first set of blades or veins and have a whirling motion imparted thereto, thereby causing heavier than air particles therein to be thrown outward by centrifugal force and follow close to the sides of the casing, and an 125 130

axial opening through each of the following
baffles for permitting spark free gases near
the axis of the casing to be passed to the out-
let without having further whirling motion
imparted thereto.

5 In testimony whereof I affix my signature.
